ATTORNEY.

UNITED STATES PATENT OFFICE

1,991,969

CONTAINER

Frederick Westerbeck, University City, Mo., Northwestern Trust Company and Emil J. Westerbeck executors of said Westerbeck, deceased

Application May 2, 1932, Serial No. 608,576

3 Claims. (Cl. 220—54)

This invention relates to containers and more specifically it relates to sheet metal cans which may be easily and effectively sealed in a vacuum.

One of the objects of this invention is to provide a container of this type which may be economically manufactured, effectively and easily sealed and readily opened.

Another object of this invention is to produce a container having a closure seamed thereto wherein the closure may be severed from the container body and removed and then reseated on the container body to effectively seal the container.

Another object of this invention is to provide the bottom closure of a container with a baffle to prevent the contents of the container from being withdrawn with the air when the air is being exhausted from the interior of the container.

A further object is to produce a bottom closure which may be frictionally secured to the container body after the air has been exhausted to prevent the admission of air both before and during the period in which the bottom closure is seamed to the body of the container.

With the foregoing and other objects in view, the invention comprises the novel construction, combination and arrangement of parts herein-after more specifically described and illustrated in the accompanying drawing, wherein is shown the preferred embodiment of the invention. However, it is to be understood that the invention comprehends changes, variations and modifications which come within the scope of the claims hereunto appended.

Fig. 1 is a top view of a container embodying the features of this invention.

Fig. 2 is a side view showing the container in a sealed condition.

Fig. 3 is a top view of a seamless collar adapted to be located within the container.

Fig. 4 is an enlarged fragmentary vertical section taken on the line 4—4 of Fig. 3.

Fig. 5 is an enlarged vertical section taken on the line 5—5 of Fig. 1.

Fig. 6 is an enlarged fragmentary vertical section showing the position the bottom closure may occupy when the air is being exhausted from the container body.

In the drawing 7 designates a cylindrical can body having its upper edge 8 seamed to a top closure 9. The body portion 7 may be provided with grooves 10 substantially below its upper margin 11 to provide a weakened portion or removable tearing strip 12. The tearing strip 12 may be provided with a tongue 13, as shown in Fig. 2, where-

by the tearing strip 12 may be removed to sever the top closure 9 from the body portion 7. When this strip is removed, the upper margin 11 of said body portion 7 provides closure flange depending from the top seam to frictionally engage the outer face of a seamless collar 14.

This seamless collar 14 may be located within the cylindrical body portion 7 and surrounded by the upper margin 11 and tearing strip 12, as shown in Fig. 5. The seamless collar 14 may be provided with a substantially horizontal inturned baffle flange 15 at its upper portion and a down-turned inner friction member 16 at the inner edge of said inturned baffle flange 15. As shown in Figures 4 and 5, the lower edge of the friction member 16 may be folded at 17 to provide a rounded surface to prevent injury to the hands of the user.

The top closure 9 is provided with an annular friction member in the form of a downwardly extending portion 18 which frictionally engages the downturned inner friction member 16 on the seamless collar 14.

The outer face of the seamless collar is provided with a friction surface 19 frictionally engaged by the upper margin 11 of the body portion 7. The seamless collar may be beaded to the body portion 7 in an annular area 20 below said tearing strip 12 so that the seamless collar will be secured to the body portion after the tearing strip 12 has been removed.

A bottom closure 21 may be provided with a channel shaped outer margin 22, which is adapted to be seamed to the lower edge 23 of the body portion 7, as shown in Figures 5 and 6. If it is desired, a sealing material 27 may be located in the channel shaped outer margin to effectively seal the seam. The bottom closure 21 may be provided with an integral annular two-ply baffle flange 24 having an inwardly inclined folded lower edge 25.

When the air is to be exhausted from the body portion, the container is inverted and placed in any suitable vacuum chamber and the bottom closure 21 is loosely located on the container so that the lower portion of the flange 24 extends into the can body 7. The air may then be exhausted from the interior of the container and the baffle flange 24 will prevent the contents of the can from being withdrawn with the air.

After the air has been exhausted from the interior of the container, the bottom closure may be forced downwardly onto the body portion so that the baffle flange 24 occupies a position, such as shown in Fig. 5. The baffle flange 24 is pro-

vided with a friction face 26, which engages the inner face 28 of the body portion 7 to prevent the admission of air to the interior of the container.

5 The bottom closure may then be seamed to the lower edge 23 of the body portion 7 with any suitable seaming device.

10 When the container is in a sealed condition, such as shown in Fig. 5, the container may be opened by removing the tearing strip 12 and lifting off the closure 9. The flange 15 on the seamless ring 14 will serve as a baffle to limit the discharge of the contents of the container. This is a very substantial advantage in pouring coffee and other material from the container when it 15 is full, or almost full, as the inturned baffle flange then prevents, or reduces, the spilling which ordinarily results in accidental discharge of too much of the material poured from a full can.

20 When the closure is replaced on the body portion 7, the downturned flange 16 on the seamless collar 14 will frictionally engage the depressed portion 18 of the closure, and the outer face 19 of seamless collar 14 will frictionally engage the 25 margin 11 to effectively secure and seal the closure to the body portion 7 of the container.

30 A double seal is thus formed between the closure and the inner and outer faces of the collar 14, and this aids in preserving the flavor and aroma of the coffee after the tearing strip 12 is removed.

35 This separate collar 14 not only provides the inturned baffle flange 15, and the double friction seal at its elements 16 and 19, but it also serves as a shield to prevent injury to the hands of the user. When the tearing strip 12 is removed, there is a sharp edge at the top of the can body 40 which surrounds the collar 14, but the collar extends upwardly from this sharp edge and provides a smooth surface at the top of the can body.

45 The elements of the simple collar 14 thus perform three separate and distinct functions in preventing injury to the user, forming a double friction seal to preserve the contents of the container, and providing a baffle 15 to prevent the usual excess spilling when the material is poured from the container.

I claim:

50 1. A vacuum can comprising a body portion, a top closure member seamed to the upper edge of said body portion, and a seamless collar located within said body portion and surrounded by the upper margin thereof, said seamless collar being provided with an inturned baffle flange and a downturned inner flange at the inner edge of said

5 inturned baffle flange, said body portion being provided with a weakened portion to provide a removable tearing strip, said weakened portion being substantially below the seamed portions of said closure and upper edge of said body portion to provide a substantial friction seal between the closure and the seamless collar when said tearing strip is removed.

2. A vacuum can comprising a cylindrical body portion, a top closure member seamed to the upper edge of said body portion, a seamless collar located within said cylindrical body and surrounded by the upper margin thereof, said seamless collar having a substantially horizontal inturned baffle flange at its upper portion and a downturned inner friction member at the inner edge of said inturned baffle flange, said downturned friction member being folded at its lower edge to provide a rounded surface, said top closure being provided with an inwardly extended portion frictionally engaging said inturned baffle flange and a downwardly extended portion frictionally engaging said downturned inner friction member, said cylindrical body portion being grooved a substantial distance below the seamed portions of said closure member and cylindrical body portion to provide a removable tearing strip, the outer face of said seamless collar being provided with a friction surface frictionally engaged by said upper margin of the cylindrical body portion in the substantial area above said removable tearing strip, and said seamless collar being beaded to said cylindrical body portion in an annular area below said tearing strip.

3. A vacuum can comprising a body portion, a top closure member seamed to the upper edge of said body portion, said body portion having a weakened portion substantially below its upper margin to provide a removable tearing strip, and a seamless collar located within said body portion and surrounded by said tearing strip, the top of said seamless collar having an inturned baffle flange extending inwardly a substantial distance to prevent free discharge of the contents of the can in the area below said baffle, said weakened portion being substantially below the seamed portions of said closure and the upper edge of said body portion to provide a closure flange depending from the seam to frictionally engage the outer face of said seamless collar when the tearing strip is removed, and said seamless collar being secured to said body portion below said weakened portion.

FREDERICK WESTERBECK.
